UNITED STATES PATENT OFFICE

2,510,482

PILOT BURNER USING GASEOUS FUEL AND AIR UNDER PRESSURE

Kurt A. Scharbau and Albert Stadler, Rockford,
Ill., assignors to Eclipse Fuel Engineering Co.,
Rockford, Ill., a corporation of Illinois

Application May 30, 1945, Serial No. 596,632

1 Claim. (Cl. 158—115)

1

The present invention relates generally to pilot burners. More particularly the invention relates to that type of pilot burner which is adapted to ignite and maintain in operation a gas burner, such, for example, as a tube variety burner for an industrial furnace or other heating apparatus, comprises a tubular body having means at one end for supplying it with gas and air, and serves when in operation to direct a flame toward the main burner.

It has heretofore been proposed to utilize in connection with a main gas burner a pilot burner of the entrainment type, i. e., a pilot burner wherein the tubular body is provided at its receiving end with a nozzle for jetting raw gas under pressure in stream form longitudinally through the body interior and has transverse inlet ports in its central portion for admitting air under atmospheric pressure into, and for admixture with, the stream of raw gas emanating from the nozzle. In practice it has been found that a pilot burner of the entrainment type is not reliable when it is supplied with butane, propane, natural gas, or any other gas having a high calorific value because of the tendency of the flame to become extinguished when the air ports in the body are subjected to any appreciable draft.

One object of the invention is to provide a pilot burner of the type under consideration which is an improvement upon, and eliminates the objections to, pilot burners of the entrainment type and is characterized by the fact that it is capable of burning any gas of high calorific value without likelihood of extinguishment of the flame as the result of the body being subjected to a draft or unusual exterior air currents.

Another object of the invention is to provide a pilot burner of the type and character under consideration in which the tubular body is provided at its inlet end with a mixing chamber, a nozzle for jetting air under superatmospheric pressure across the chamber and thence through the body, and means independent of the nozzle for supplying raw gas to the chamber, and embodies within its discharge end a baffle unit for reducing the velocity of the mixture of gas and air under pressure.

A further object of the invention is to provide a pilot burner of the type under consideration which is generally of new and improved construction, may be manufactured at a low and reasonable cost and is so designed that it possesses extremely long life.

Other objects of the invention and the various

advantages and characteristics of the present pilot burner will be apparent from a consideration of the following detailed description.

The invention consists in the several novel features which are hereinafter set forth and are more particularly defined by the claim at the conclusion hereof.

In the drawing which accompanies and forms a part of this specification or disclosure and in which like letters and numerals of reference denote corresponding parts throughout the several views:

Figure 1 is a top or plan view of a main tube variety burner having applied thereto a pilot burner embodying the invention;

Figure 2 is an enlarged vertical longitudinal section on the pilot burner;

Figure 3 is a perspective view of the baffle unit at the discharge end of the tubular body of the pilot burner; and

Figure 4 is a perspective view of the mounting bracket for supporting the pilot burner in operative position or relation with the main burner.

The pilot burner which is shown in the drawing constitutes the preferred form or embodiment of the invention. It is illustrated in connection with a main tube variety gas burner B and serves, as hereinafter described, to ignite the burner and maintain it in operation. A mounting bracket 6

serves to support the pilot burner in operative relation with the main burner B. The latter is of conventional or standard construction and comprises an elongated horizontally extending tube b one end of which is supported by a metallic cooling well support S. Such support comprises an annular frusto-conical side wall s and a centrally apertured inner end wall s¹ and is designed to fit in a frusto-conical hole in a wall of a furnace (not shown). The side wall s embodies at its outer end an integral outwardly extending flange s². The inner end of the burner tube b extends through the central aperture in the inner end wall s¹ of the support and is secured to said inner end wall in any suitable manner.

The burner tube is of materially greater length than the cooling well support with the result that its outer end is disposed exteriorly of the support. Said outer end of the tube is connected by a pipe connection b² to receive a combustible gas and air mixture under pressure from a source of supply. The inner periphery of the burner tube defines a throat b³, the inner end portion of which is flared in the direction of the inner end of the burner tube b. When the burner B

50 is in operation the combustible gas and air mix-

ture under pressure flows through the throat in the burner tube and burns as it emanates from the inner end of the tube. The upper portion of the inner or discharge end of the burner tube is provided with an angularly disposed orifice b^4 . This orifice is located directly outwards of the inner end wall s^1 of the cooling well support S and leads into the central part of the flared inner end portion of the throat b^3 in the burner tube. It is inclined upwards and outwards with respect to the longitudinal axis of the throat b^3 and provides means whereby the combustible gas and air mixture in transit through the throat b^3 may be ignited from the outside of the burner tube.

The pilot burner is positioned above the central portion of the burner tube b and operates, as hereinafter described, to direct a flame into the angularly disposed orifice b^4 in order to maintain in an ignited condition the gas and air mixture flowing through the throat of the burner tube. It is carried or supported by the mounting bracket 6 and comprises an elongated tubular body 7 , a nozzle 8 , a tubular tip 9 and a baffle unit 10 .

The body of the pilot burner is preferably formed of cast iron and has at one end thereof an integral, longitudinally extending, centrally disposed reduced stem 11 . The latter, as best shown in Figure 4, is provided with an external or male screw thread 12 . The interior of the tubular body 7 is shaped so as to define a cylindrical longitudinally extending open ended mixing chamber 13 at the other end of the body, and a longitudinally extending throat 14 which leads from the inner end of the chamber 13 to and through the outer end of the reduced stem 11 . The mixing chamber 13 is of materially greater diameter than the throat 14 and has a female screw thread 15 at its outer end. The throat 14 flares gradually in the direction of the stem 11 , as shown in Figure 4. The nozzle 8 of the pilot burner has an open ended centrally disposed orifice 16 extending longitudinally therethrough and is connected by a pipe connection 17 to receive air under superatmospheric pressure from any suitable source, such, for example, as an air storage tank or a compressor (not shown). One end of the nozzle extends into the outer end of the mixing chamber 13 in the tubular body 7 and embodies an external or male screw thread 18 which is in interfitting relation with the internal or female screw thread 15 and serves to secure the nozzle 8 in connected relation with the body 7 . The other or outer end of the nozzle is of materially greater diameter than said one or inner end and embodies an annular shoulder 19 which abuts against the end of the tubular body 7 having the mixing chamber 13 . The inner end of the orifice 16 is of reduced diameter and is in centered relation with, and of materially less diameter than, the small end of the throat 14 , and the outer end of the orifice is of increased diameter and has a female screw thread 20 . The pipe connection 17 includes a shut-off cock 21 , one end of the body of which extends into the outer end of the orifice 16 and has a male screw thread which interfits with the female screw thread 20 and serves to hold the cock in connected relation with the nozzle. When the cock 21 is open air under pressure flows through the nozzle 8 and then flows in jet form across the mixing chamber 13 and through the throat 14 . A gas of high calorific value, such as propane, butane or natural gas, is supplied to the mixing chamber 13 for admixture with the air under pressure by way of a pipe connection 22 and a port 23 . The pipe

connection 22 receives gas under atmospheric or superatmospheric pressure from any suitable source (not shown) and is indirectly connected to the end of the tubular body 7 having the mixing chamber 13 by way of an internally threaded nipple 24 which is formed integrally with, and extends laterally from, the body 7 . The port 23 communicates with the inner end of the nipple and leads to the inner end of the mixing chamber 13 , as shown in Figure 4. A shut-off cock $22a$ is included in the pipe connection 22 in order that the supply of gas to the body 7 may be cut off when the pilot burner is not in use and adjusted or regulated when the pilot burner is in use. One end of the body of the cock $22a$ screws into the internally threaded nipple 24 . When the cock $22a$ is open while the shut-off cock 21 is open gas enters the mixing chamber 13 via the port 23 and there mixes with the jet of air under pressure emanating from the nozzle 8 to form a combustible gaseous mixture which flows from the mixing chamber through the flared throat 14 . If the gas is not under superatmospheric pressure it is drawn into the mixing chamber 13 by aspiration. By reason of the fact that the throat 14 is flared in the direction of the stem 11 the velocity of the combustible mixture of gas and air under pressure progressively decreases as the mixture flows from the mixing chamber to and through the externally threaded stem 11 .

The tubular tip 9 is preferably formed of steel and has substantially the same external diameter as the cast iron body 7 . One end of the tip 9 surrounds the reduced stem 11 at the discharge end of the tubular body 7 and embodies an internal screw thread 25 which is in interfitting relation with the external or male screw thread 12 on the stem and serves to hold the tip of the pilot burner in connected relation. The portion of the inner periphery of the tip that is outwards of the screw thread 25 is cylindrical. It is of reduced diameter and has at the inner end thereof an annular outwardly extending shoulder 26 which faces in the direction and joins the inner end of the screw thread 25 . When the pilot burner is in operation the combustible mixture of gas and air under pressure, after passing through the flared throat 14 , flows into the tip 9 . Combustion of the mixture takes place within the tip and the flame resulting from combustion projects from the tip as the result of the velocity of the mixture entering the tip.

The baffle unit 10 is located in the central portion of the tubular tip 9 and serves so to reduce the velocity of the combustible mixture entering the tip that the mixture burns in the tip. It is preferably of one-piece design or construction and comprises a pair of laterally spaced discs 27 and 28 and a stem 29 between the two discs. The disc 27 of the baffle unit has its marginal portion clamped between the shoulder 26 and the outer end of the reduced stem 11 , and embodies inwards of its clamped margin an annular series of holes 30 . The disc 28 is of less diameter than the disc 27 and is disposed outwards of the latter. It is of slightly less diameter than the adjacent portion of the inner periphery of the tubular tip 9 and has an annular series of holes 31 . Said holes are angularly offset with respect to the holes 30 in the disc 27 in order that they are not in registry with such holes. The stem 29 is formed integrally with and extends between the central portions of the two discs 27 and 28 , and serves to hold the latter in rigid offset or laterally spaced relation. In connection with operation of the pilot burner the

combustible mixture of gas and air under pressure, after travelling or flowing through the flared throat 14, passes first through the holes 30 in the disc 27 and then through the space between the two discs. After passing through such space a portion of the mixture flows through the holes 31 in the disc 28 and the balance flows around the said disc 28. During flow of the mixture past the baffle unit 10 the velocity of the mixture is reduced to such an extent that the mixture burns within the outer end of the tubular tip 9, as hereinbefore described. Preferably there are four holes in the disc 27 and four holes in the disc 28 and the holes in the disc 27 are arranged at right angles to one another and the holes in the disc 28 are arranged at right angles to one another and are positioned 45° from the holes 30 in the disc 27. The total area of the holes in each disc of the baffle unit is materially less than the area of the discharge end of the flared throat 14 in the tubular body 7. Because of the design and construction of the pilot burner the latter is capable of burning any gas of high calorific value without likelihood of the flame emanating from the tip being extinguished by a draft or unusual exterior air currents.

The mounting bracket 6 is located at one side of the central portion of the tube b of the main gas burner B. It is I-shaped and comprises a vertically extending intermediate piece 32, an elongated horizontally extending upper crosspiece 33, and an elongated horizontally extending lower crosspiece 34. The upper end of the vertically extending intermediate piece 32 is provided with a cylindrical part 35 having a centrally disposed longitudinally extending bore 36. The tip 9 of the pilot burner extends through the bore 36 and is releasably secured in place by means of a set screw 37 which extends through a screw threaded hole in the outer side portion of the cylindrical part 35. The pilot burner is arranged so that the tubular tip 9 thereof is disposed within the cooling well support S. The bore 36 in the cylindrical part 35 on the upper end of the intermediate piece 32 of the mounting bracket is so canted or angularly arranged that when the pilot burner is in assembled relation with the mounting bracket the axis of the tubular tip 9 is substantially in alignment with the outer end of the angularly disposed orifice b⁴ in the upper portion of the discharge end of the tube b of the main burner B and hence the flame emanating from the tip of the pilot burner is directed towards the orifice. The upper crosspiece 33 of the mounting bracket 6 is positioned adjacent the upper portion of the flange s² of the cooling well support S and is secured thereto by way of a bolt 38, the shank of which extends through a horizontal slot 39 in the upper crosspiece 33 and fits within a threaded hole in said upper portion of the flange s². The lower crosspiece 34 of the mounting bracket is positioned adjacent the lower portion of the flange s² and is secured in place by means of a bolt, the shank of which extends through a horizontal slot 41 in the cross piece 34 and fits in a threaded hole in said lower portion of the flange s². The slots 39 and 41 permit the mounting bracket to be adjusted laterally with respect to the tube b of the main burner B and also permit the bracket to be tilted about its center in either a clockwise or counterclockwise direction. The ends of the upper crosspiece 33 of the mounting bracket are provided with transversely extending set screws 44 and these abut against the upper portion of the flange s² of the cooling well support S and

make it possible angularly or rotatively to adjust the bracket about its longitudinal center or axis. By adjusting the mounting bracket 6 laterally by way of the slots 39 and 41 and angularly or rotatively adjusting the bracket by way of the set screws 44 the bracket may be so positioned that the axis of the tubular tip 9 of the pilot burner intersects or is in alignment with the angularly disposed orifice b⁴ in the upper portion or discharge end of the tube b of the main gas burner B. The central portion of the vertically extending intermediate piece 32 of the mounting bracket is provided with an integral laterally extending lug 45 which fits within a groove in the main burner tube b and serves to hold the main burner tube against rotation relatively to the bracket 6 and the cooling well support S.

When it is desired to mount the pilot burner with respect to the main burner B the tip 9 is inserted through the bore 36 in the cylindrical part 35 at the upper end of the vertically extending intermediate piece 32 of the mounting bracket 6 and is secured in place by tightening the set screw 37. Thereafter the bracket with the pilot burner connected thereto is positioned along side of the central portion of the main burner tube b and is shifted laterally in order to bring the laterally extending lug 45 into interfitting relation with the aforementioned groove. After so positioning the bracket the bolts are inserted through the slots 39 and 42 and are screwed part way into their respective threaded holes in the flange s² of the cooling well support S. After such operation the bracket is adjusted laterally and tilted to the proper extent and then is angularly or rotatively adjusted about its center by adjustment of the set screws 44. When the bracket is so positioned that it serves to hold the pilot burner in such position that the axis of the tubular tip 9 is in alignment or intersecting relation with the orifice b⁴ the bolts are tightened to the fullest extent.

When it is desired to operate the main gas burner B the pilot burner is lighted by first opening the shut-off cocks 21 and 22^a and then placing a lighted match adjacent the discharge end of the tubular tip 9. As soon as the pilot burner is ignited or lighted it produces a flame which is directed into the angularly disposed orifice b⁴ in the discharge end of the main burner tube b. Upon supply of a mixture of gas and air under pressure to the main burner tube the mixture is ignited in the flared discharge end of the throat b³ of the main burner tube by the flame which enters the main burner tube via the orifice b⁴.

The herein described pilot burner effectively and efficiently fulfills its intended purpose and as previously pointed out is characterized by the fact that it is capable of burning any gas of high calorific value without likelihood of extinguishment of its flame as the result of the body of the pilot burner being subjected to a draft or unusual exterior air currents. It is contemplated that the pilot burner will be in operation at all times during operation of the main burner in order that it will ignite the main burner should the latter go out as the result of a back-fire.

The invention is not to be understood as restricted to the details set forth since these may be modified within the scope of the appended claim without departing from the spirit and scope of the invention.

Having thus described the invention what we

claim as new and desire to secure by Letters Patent is:

A pilot burner comprising an elongated body embodying at one end thereof an open ended mixing chamber and a transverse port leading to the inner end of the chamber, and having a longitudinally extending throat leading from the chamber to and through its other end and flared in the direction of the latter, a nozzle mounted snugly in the outer end of the mixing chamber, having a discharge orifice facing, and in centered relation with, the small end of the throat, and provided with means for supplying it with air under superatmospheric pressure, means connected to said one end of the body for supplying raw gas to the port for entry into the mixing chamber and admixture with air under superatmospheric pressure, a separately formed tubular tip having one end thereof surrounding, and connected by a screw thread connection to, said other end of the body, forming a combustion chamber in communication with, and of greater diameter than, the large end of the throat, and provided with an internal annular shoulder adjacent said other end of the body, and a baffle unit disposed in said one end of the tip adapted to reduce the velocity of the air and gas mixture as it flows into the combustion chamber from the throat, and embodying an inner transversely extending disc having the marginal portion thereof clamped between the shoulder and

said other end of the body and provided with transverse holes therein, and an outer transversely extending positioned and maintained disc in laterally spaced relation with the inner disc, 5 having the outer marginal portion thereof spaced a small distance inwards from the inner periphery of the tip, and provided with transverse holes therein in offset relation with the holes in the inner disc.
